UNITED STATES PATENT OFFICE

2,552,392

SPADE TYPE ELECTRIC CONNECTOR

Hugh W. Batcheller, Newton Highlands, Mass.

Application September 3, 1949, Serial No. 113,943

3 Claims. (Cl. 173—363)

1

This invention relates to an electric connector by which the ends of two wires can be connected and disconnected electrically. As is usual, the connector consists of two cooperating members, each of which is secured to the end of one of the wires to be connected. Many connectors have heretofore been produced for connecting and disconnecting conductors. The object of the present invention is to provide an improved connector characterized by economy of manufacture, reliability in operation and improved interfacial contact to reduce the electrical resistance of the connector.

The connector embodying the invention is of the type described in my copending application, Serial No. 67,488, filed December 27, 1948, and consists of male and female members, the male member comprising essentially a flat plate or tongue to be received by the female member. The latter has a plane bottom portion with overhanging flanges arranged to press the male member strongly against the bottom portion to ensure firm interfacial contact. This is done by shaping the overhanging flanges of the female member so that each has a low point with a clearance above the bottom slightly less than the thickness of the male tongue. The side walls supporting the flanges are preferably cut away to reduce their stiffness and to make it possible for the flanges to yield slightly upward when the tongue is thrust thereunder.

For a more complete understanding of the invention, reference may be had to the following description thereof, and to the drawing, of which—

Figure 1 is a perspective view of the two members of a connector embodying the invention;

Figure 2 is a section on the line 2—2 of Figure 1;

Figure 3 is a section on the line 3—3 of Figure 1;

Figure 4 is a plan view of the connector with the members connected; and

Figure 5 is a section on the line 5—5 of Figure 4.

The female member of the connector can conveniently be made by shaping a blank which has been cut from sheet or strip stock of suitable metal, such as copper, brass, or bronze. This member consists of a flat bottom portion having side walls 12 and 14 bent up at right angles thereto. These side walls are turned in to form flanges 16 and 18 which overhang portions of the bottom plate. The metal stock from which the blank for this member is cut is preferably of sufficient thickness to provide a considerable degree of rigidity in an object of the size of the members

2

of the connector shown on the drawing. In order to increase the resilience of the side walls 12 and 14, these walls may be cut away between the bottom plate 10 and the flanges 16 and 18 to form openings 20 and 22, leaving the end portions of the walls as supporting elements for the flanges. The effect of cutting away a portion of each wall is to reduce its stiffness so that the flanges can yield more readily when pressure is brought to bear on them. While it is convenient to cut away the central portion of each wall, as shown, the end portions can be cut away instead, leaving the central portion to support the flange.

The flanges 16 and 18 are shaped so that they slope longitudinally and are in the form of a V with a very wide angle, the apex of the V preferably coming at or near the mid-point of each flange. In other words, each flange slopes gradually downward from both ends toward an intermediate point of minimum clearance from the bottom 10.

The female member is also provided with a tubular portion 24 adapted to receive the end portion of copper wire 26 and to be pressed upon the wire so as to grip it. A tubular portion 28 of larger diameter may be provided also to receive the end portion of the insulation 29 of the wire. The tubular portions 24 and 28 are preferably integral with the bottom 10.

30 The male member includes a plane tongue 30 having a width slightly less than the distance between side walls 12 and 14 of the female member and having a thickness slightly greater than the minimum clearance between the flanges and

35 the bottom of the female member. The male member is preferably, but not necessarily, provided with indentations 32 in one or both faces thereof, located to receive the points of minimum clearance of the flanges 16 and 18 when the two members of the connector are joined together. Laterally projecting ears 34 may be formed on the male member to act as stops and by engaging the ends of the walls 12 and 14 when the member has been thrust to its proper position under the flanges 16 and 18.

40 The male member is preferably provided with tubular elements 36 and 38 which are adapted to be pressed on the stripped end portion of the wire 40 and on its insulation 42, respectively.

45 Since the faces of the tongue 30 are plane and uninterrupted except for the small recesses 32, there is a large area of interfacial contact between the bottom of the tongue 30 and the floor of the bottom portion 10 of the female member.

50 The stiff resilience of the side walls 12 and 14

and of the flanges 16 and 18 causes the flanges to press the tongue 30 strongly against the floor of the female member so that a good electrical connection is had between the members if the connection is had between the members if the interfacial surfaces are kept clean. The lower-most points of the flanges enter the recesses 32 in the upper face of the tongue 30 and tend to hold the members in their assembled relation so as to prevent accidental disconnection.

I claim:

1. An electric connector consisting of male and female members of sheet metal, the female member having a flat bottom portion with bent-up side walls and inturned flanges overhanging said bottom portion, a substantial mid-portion of each side wall being cut away, the portion of each said flange above the cut-away portion of the corresponding side wall being downwardly bent to a V-shape with the angle of the V approximately at the mid-point of the flange, said male member comprising a flat tongue slightly thicker than the clearance between each said angle and the bottom surface beneath, said male member having indentations extending in its face to receive said angles.

2. A female member of an electric connector, comprising a flat sheet metal bottom portion with bent-up side walls and inturned flanges overhanging said bottom, said flanges each being shaped to slope longitudinally to form a wide-angled V whereby the underface of each flange

slopes gradually downward from the ends thereof to an intermediate point of minimum clearance from the surface of said bottom, said side walls having portions cut away to reduce their stiffness.

3. A female member of an electric connector, comprising a single piece of sheet metal having a plane bottom portion with bent-up side walls and inturned flanges on the side walls overhanging said bottom, each side wall having a substantial portion thereof cut away between the ends thereof whereby the stiffness of the side walls is reduced, each said flange being shaped to a wide-angled V-form whereby the under surface slopes gradually from the ends of the flange to an intermediate point of minimum clearance over said bottom.

HUGH W. BATCHELLER.
